UNITED STATES PATENT OFFICE

AUGUSTIN J. CHEVRETTÉ, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTOR CONTROLLING DEVICE

Application filed December 28, 1929. Serial No. 417,241.

This invention relates to automatic weft replenishing looms in which substantial exhaustion of weft in the running shuttle is indicated by a weft detector. In certain types of weft replenishing looms, the weft detector is at the non-replenishing side of the loom and the indicated shuttle is replenished on the third pick after indication. The indicated shuttle thus returns once to the weft detecting side of the loom after indication but before shuttle change or weft replenishment.

It is the object of my invention to provide improved means to prevent a second indication of weft exhaustion when a shuttle returns to the detecting side of the loom prior to replenishment or shuttle change. My invention is particularly applicable to a shuttle changing loom of the type disclosed in my prior Patent No. 1,753,233, issued April 8, 1930, and it is a further object of my invention to provide means for disabling the weft detector when the shifting shuttle boxes are raised for a shuttle change.

My invention further relates to arrangements and combinations of parts which will be hereinafter described and more particularly pointed out in the appended claims.

A preferred form of the invention is shown in the drawings, in which

Fig. 1 is a front elevation of parts of a shuttle changing loom embodying my improvements;

Fig. 2 is a side elevation of certain parts, looking in the direction of the arrow 2 in Fig. 1;

Fig. 3 is a right hand side elevation, looking in the direction of the arrow 3 in Fig. 1;

Fig. 4 is a plan view of the weft detecting mechanism, looking in the direction of the arrow 4 in Fig. 1;

Fig. 5 is a front elevation of the detecting mechanism, looking in the direction of the arrow 5 in Fig. 4; and

Fig. 6 is a detail plan view, looking in the direction of the arrow 6 in Fig. 2.

Referring to the drawings, I have shown portions of a loom frame 10 on which shuttle changing mechanism M is mounted. This mechanism is of the type shown in my prior patent and need only be described in a gen-

eral way in this application. The mechanism includes regular and auxiliary shuttle boxes indicated generally at 12 and mounted on a lifter rod 13. During normal running of the loom, the boxes are in their lowered position, but are raised after indication of transfer so that a new shuttle will be placed in the upper box and the running shuttle will be received in the lower box, from which it is thereafter discharged.

The mechanism for actuating the lifter rod 13 is indicated in Figs. 2 and 6 and comprises a lifter lever 15 pivoted at 16 to the loom frame and having a give-way connection 17 to the lifter rod 13. A second or actuating lever 20 is loosely mounted on the stud or shaft 16 and is provided with a cam roll 21 positioned in the path 22 of a side cam 23. An offset portion 25 of the lever 20 extends below and in front of the lever 15.

A latch 27 is pivoted at 28 on a lug 30 projecting outward from the lever 20. The latch 27 normally rests on a shoulder of the lever projection 25 and may be moved under the lever 15 into a slot 32 in the actuating lever 20.

A spring 33 normally holds the latch 27 in the inoperative position indicated in Fig. 6, in which position the actuating lever 20 swings freely and the lifter lever 15 remains at rest. When the latch 27 is moved under the lever 15, the lever 15, lifter rod 13, and boxes 12 are raised.

The latch 27 is provided with a downward projection 35 (Fig. 2) to which a wire or rod 36 (Figs. 1 and 6) is connected. The rod 36 is made yielding by the introduction of a spring 37 between the ends thereof. The right hand end of the rod 36 is connected to a bell crank 38 pivoted at 39 on the loom frame 10.

A link 40 connects the bell crank 38 to a floating lever 41 (Figs. 4 and 5) which is pivoted at 42 to the upper end of an actuating rod or plunger 44. At its lower end, the plunger 44 (Fig. 3) has a give-way connection 45 to a lever 46 which is regularly oscillated by a side cam 47.

Under normal conditions, the floating lever 41 swings freely about its pivotal connection 400

48 to the upper end of the link 40. If, however, the downward movement of the right hand end 49 of the lever 41 is prevented, the pivot of the lever is thereby transferred to the end 49 of the lever and the link 40 is forced downward, moving the rod 36 to the right in Fig. 1, and moving the latch 27 to operative position under the lifter lever 15. If the lever 15 is in the path of the latch, the spring 37 yields and the latch 27 snaps under the lever 15 as soon as the latch is moved downward to clear the lever 15.

The parts thus far described are substantially as shown in my prior patent, to which reference is made for further details.

A weft detector 50 (Figs. 4 and 5) is pivoted to a slide 51 movable forward and rearward in guideways in a stand 52 supported on a bracket 53. The slide is held yielding rearward by a spring 54 disposed within the stand 52. An indicating member 60 is pivoted at 61 below the stand 52 and is held normally in the full line position of Fig. 5 by a weighted arm 63.

When the weft detector 50 engages a bobbin having an insufficient supply of yarn, the end of the detector slips along the barrel of the bobbin in the direction of the arrow *a* in Fig. 4 and the forwardly extending end 65 of the detector moves the member 60 from the full line to the dotted line position in Figs. 4 and 5, in which latter position the member 60 underlies the end 49 of the lever 41 and prevents downward movement thereof. The lever 41 then pivots on the member 60, as previously described, and indicates a shuttle transfer.

In order to prevent a second indication when the substantially exhausted shuttle returns to the weft detecting side of the loom before transfer, I provide a lever or arm 70 mounted on a fixed pivot 71 and engaging the member 60 when swung to the right (as viewed in Fig. 5). Such engagement of the member 60 by the member 70 prevents movement of the member 60 to the dotted line position in Fig. 5 and thus prevents a second indication of weft exhaustion.

The arm 70 has a laterally projecting portion 72 connected to a rod 73 extending down through a guide or bearing 74 (Fig. 3) and normally held upward by a light spring 75 engaging a collar 76 on said rod.

At its lower end, the rod 73 is connected to a chain 77 passing around a guide pulley 78 and connected by a rod 79 (Fig. 1) to a lever 80 pivoted on a short shaft 81 at the left hand side of the loom. A spring 82 (Fig. 2) encircles the shaft 81 and is of sufficient strength to overcome the light spring 75 previously described. An arm 84 (Fig. 1) extends under a stud 85 on the lifter lever 15.

The weight of the lever, together with the attached parts, is sufficient to overcome the spring 82 under normal running conditions.

When the lifter lever 15 is raised, however, upon indication of weft exhaustion, the stud 85 is removed from engagement with the arm 84, and the spring 82 becomes effective to depress the rod 73 and arm 72 and to swing the arm 70 against the member 60, holding the same in inoperative position.

I have thus provided simple and effective connections by which the weft detector is rendered inoperative when the shuttle boxes are raised after indication of weft exhaustion and prior to a shuttle change. The provision of such an attachment is extremely desirable to prevent the possibility of repeated and unnecessary shuttle changes.

Having thus described my invention and the advantages thereof, I do not wish to be limited to the details herein disclosed, otherwise than as set forth in the claims, but what I claim is:—

1. In a weft replenishing loom, shifting shuttle boxes at one end of the loom having a normal running position and a replenishing position, weft replenishing mechanism associated with said shifting shuttle boxes, a weft detecting device at the other end of the loom, normally inoperative means to shift said shuttle boxes, said means being rendered operative by said weft detecting device upon indication of weft exhaustion, and means to render said weft detecting device inoperative whenever and so long as said boxes are removed from normal running position.

2. In a weft replenishing loom, shifting shuttle boxes at one end of the loom having a normal running position and a replenishing position, a weft detecting device at the other end of the loom, normally inoperative means to shift said shuttle boxes including a floating lever and an actuator therefor, a member movable into the path of said lever by said detecting device upon indication of weft exhaustion, and means to prevent such movement of said member by said detecting device on the return of the shuttle to the detecting side of the loom prior to weft replenishment.

3. In a weft detecting loom, shifting shuttle boxes at one end of the loom having a normal running position and a replenishing position, a weft detecting device at the other end of the loom, a floating lever, an actuator therefor, a member engaged by said detecting device and movable into the path of said floating lever, thereby rendering said lever operative, and means to prevent such movement when said boxes are out of normal running position.

4. In a loom, a floating actuating lever, a member movable into the path of said lever and effective to change the pivotal axis thereof, weft replenishing mechanism, and means controlled thereby effective to prevent a second movement of said member into the path of said lever during weft replenishment and

after said weft replenishing mechanism has received an initial operative movement.

5. In a weft replenishing mechanism, a weft detecting device, disabling means therefore, a set of shifting shuttle boxes at one end of the loom having a normal running position and a replenishing position, weft replenishing mechanism associated with said shifting shuttle boxes, connections by which 10 said disabling mechanism is held inoperative as long as said boxes remain in normal running position, and a spring effective to render said disabling mechanism operative when said boxes are moved from normal running position to weft replenishing position.

15 In testimony whereof I have hereunto affixed my signature.

AUGUSTIN J. CHEVRETTE.
